UNITED STATES PATENT OFFICE.

REUBEN B. BENJAMIN, OF CHICAGO, ILLINOIS, ASSIGNOR TO BENJAMIN ELECTRIC MANUFACTURING COMPANY, OF CHICAGO, ILLINOIS, A CORPORATION OF ILLINOIS.

SEPARABLE ATTACHMENT-PLUG.

1,250,080.

Specification of Letters Patent. Patented Dec. 11, 1917.

Original application filed November 21, 1908, Serial No. 463,764. Divided and this application filed August 13, 1915. Serial No. 45,296.

To all whom it may concern:

Be it known that I, REUBEN B. BENJAMIN, a citizen of the United States, residing at Chicago, in the county of Cook and State of Illinois, have invented new and useful Improvements in Separable Attachment-Plugs, of which the following is a full, clear, concise, and exact description, reference being had to the accompanying drawing, forming 10 a part of this specification.

My invention relates to separable attachment plugs, which, as is well known, consist of two members, one of which is provided with contacts for coöperation with the contacts of the socket, and the other of which carries binding terminals, these members being detachably connected together in such manner that, when assembled, electrical connection is made between the contacts on the 15 one member and the binding terminals on the other member. Such a plug is shown in my copending application Serial No. 463,764, filed Nov. 21, 1908, of which application this application is a division.

One of the objects of my invention is to provide improved means for relieving the binding terminals from strain due to a pull on the conductors.

Further objects will appear from the detailed description to follow and from the appended claims.

In the accompanying drawings in which I have shown one embodiment of my invention—

Figure 1 shows the binding terminal carrying member separated from the other member;

Fig. 2 is a plan view of the binding terminal carrying member;

Fig. 3 is an inverted plan view of the other member;

Fig. 4 is a vertical axial section of the plug; and

Fig. 5 is a reduced fragmentary view of one of the details of the device.

In the form of my invention illustrated herein, the part which carries the socket terminal engaging contacts consists of a shell 10, adapted for insertion into the socket, and 10 a body 11, which carries binding terminals to which are secured the flexible conductors leading to the fan or other electric current consuming device, the body 11 being remova-

bly inserted in the shell 10, as will be herein-after fully described.

The shell 10 comprises a metallic sleeve 12 having screw threads formed thereon adjacent its upper end for engaging the internal threads of an ordinary Edison socket. This sleeve 12 is formed with an inwardly turned upper end flange 14 and an outwardly turned lower end flange 13, and with an inwardly extending circumferential bead 15 and an outwardly extending circumferential bead 16 intermediate its ends, the beads 15 and 16 being preferably located adjacent each other and immediately below the termination of the screw threaded portion of the sleeve. Surrounding the lower portion of the sleeve 12, and held between the flange 13 and the bead 16, is a ring 17, formed of insulating material, such as hard rubber or the like, and having an outwardly extending flange 18 which is preferably knurled at its periphery to provide a firm hold for the fingers of the user. A cup-shaped block 19 of insulating material is inserted in the upper end of the sleeve 12 and has formed thereon an outwardly extending flange 20 which abuts against the flange 14. The block 19 is held in place by an insulating ring 21 located between the lower side of its flange 20 and the bead 15 of the sleeve 12.

The block 19 is formed with a central aperture 22 in which is secured the center contact of the plug. The center contact consists of a tubular member 23 which passes through the aperture 22 and is bent outward to form a flange 24 outside the block 19. The tubular member 23 is also formed with a flange 25, within the block 19. One end of a resilient inner contact 26, which preferably consists of a substantially U-shaped plate of spring brass, surrounds the tubular member 23 and is clamped between the flange 25 and the inner side of the block 19.

The sleeve 12 is formed with inwardly extending bayonet projections 27 adjacent its lower edge, said projections tapering slightly upward to one side for a purpose to be herein-after described. A small excrescence 28 is formed adjacent the thicker end of one of the projections 27.

By building up the shell as above described, instead of, as is usual in earlier forms of separable plugs, constructing it of

a single hollow porcelain part having a sleeve contact secured thereon, a larger space is provided within the shell, thus enabling the body to be made of larger proportions than has hitherto been considered possible. This is an important advantage of the plug since it enables the insulating properties of the body to be increased, and the binding terminals to be so located on the body as to 10 be readily accessible.

The body 11 comprises an insulating base 29 of less diameter than the internal diameter of the sleeve 12 and having a tapered portion 30 at its upper end. The base 29 is formed with a side recess 31 extending from one end thereof to the other for containing the end of the conductor 32. A second recess 33 is also formed at the upper end of the plug, a passage 34, which opens 20 at one end into the recess 33, extending through the plug and having an enlarged portion 35 at the end thereof adjacent the lower face of the plug.

Located in the recess 33 is the shank 36 25 of the end contact 37 of the body, the end contact resting upon the upper end of the base 29, and having its shank bent downwardly and outwardly to snugly fit in the recess 33. The shank 36 has an aperture 30 formed therein, which, when the end contact is in position, registers with the passage 34, and a hollow metallic rivet 38 is passed through this aperture and the passage 34 and flanged over at one end against the shank 36 and at the other end against the shoulder formed by the enlargement 35 of the passage 34. This rivet securely holds the shank 36 in position in the recess 33. The shank 36 is further provided with a 40 binding terminal 39 to which is secured the end of the conductor 40 which is passed upwardly through the enlargement 35 and the hollow rivet 38.

Surrounding the lower end of the base 29 45 is a cup 41 constructed of brass or other electric current conducting material and of a diameter slightly less than the inner diameter of the sleeve 12. The cup 41 is reduced at its lower end to form a shoulder 50 41^a and a downwardly extending collar 42, which latter is screw threaded. The base is secured in the cup by bending portions of the upper edge of the latter over ledges formed upon the base. Secured, by rivets, 55 or otherwise, to the cup 41, and so located as to enter the recess 31, is a conductor plate 44 preferably so shaped that sufficient room is left between it and the inner face of the recess 31 to allow of the passage of the bared end of the conductor 32 therethrough, an upwardly bent lug 45 being formed on the conductor plate 44 for the purpose of precluding any chance of the conductor slipping around the conductor 60 plate to the outside thereof. A binding

terminal 46 is screwed into the conductor plate 44 and clamps the end of the conductor 32. The cup 41 is bent inwardly at one or more points at its periphery to form recesses 47, such recesses being of the same number as the bayonet projections 27 on the sleeve 12 of the shell 10, and so located as to register with the projections 27 when the body 11 is inserted in the shell 10. Flat pieces 48 are formed upon the 75 base 29 in order that the bending in of the cup 41 to form the recesses 47 may be possible. Screwed into the collar 42 is the screw threaded neck 49 of the handle 50, which is constructed of hard rubber or other 80 insulating material, and is formed with an upturned flange or skirt 51 which incloses the collar 42. The conductors 32 and 40 pass through the neck 49, which latter is of such length that, when screwed firmly 85 into the collar 42, it clamps the conductors against the lower end of the base 29 and precludes any chance of their detachment from the binding terminals by an accidental jerk or the like. 90

In using the plug, the shell 10 is screwed into the socket until the flange 24 of its center contact makes connection with the center contact of the socket. When thus connected, the shell 10 co-operates with the 95 Edison socket to form a socket of a different internal configuration, and, of the socket so formed, 26 is one contact and the lower portion of the sleeve, 12 the other. The body 11 then becomes a plug, the end contact 37 and cup 41, to which the conductors 40 and 32 are respectively connected, engaging the inner contact 26 and the inner face of the sleeve 12. 100

The body 11 and shell 10 are preferably 105 so proportioned that, when the body is inserted in the shell (the projections 27 of the shell entering the recesses 47 of the body), the end contact 37 will engage the inner contact 26 of the shell slightly before 110 the projections 27 reach the lower end of the recesses 47, so that it is necessary to compress the inner contact 26, which is made resilient to that end, before the projections can pass beyond the lower end of the cup 115 41. When the body 11 has been thus forced against the inner contact 26 until the projections 27 have passed through the recesses 47 and beyond the lower end of the cup, it is turned relatively to the shell so that the 120 projections 27 engage beneath the shoulder 41^a of the cup 41 and are held in such engagement by reason of the resilience of the inner contact 26. The upward slope of the projections 27 causes the end contact 37 to 125 be forced more firmly against the inner contact 26 when the body is rotated. The stop 28 limits the possible turning movement of the body in the shell.

In order to connect the body to the shell, 130

all that is necessary is that the body be firmly pushed into place and given a slight twist, while a slight twist in the opposite direction is sufficient to detach it.

5 Having thus described my invention what I claim as new and desire to secure by Letters Patent is:—

1. A separable attachment plug comprising an insertible portion having a contact 10 for engagement with the contact of a receptacle, and a portion having a quick detachable connection with said first portion, a binding terminal supported by said second portion, and conductor gripping means also 15 supported by said second portion.

2. A separable attachment plug comprising an insertible portion having a shell contact for engagement with the shell contact of a receptacle, and a portion having a quick 20 detachable connection with said first portion, a binding terminal supported by said second portion, and conductor gripping means also supported by said second portion.

25 3. A separable attachment plug comprising an insertible portion having a contact for engagement with the contact of a receptacle, and a portion having a quick detachable connection with said first portion, 30 a binding terminal supported by said second portion, and conductor gripping means also supported by said second portion, said conductor gripping means comprising a tubular thumb piece through which said conductor extends.

4. A separable attachment plug comprising an insertible portion having a contact for engagement with the contact of a receptacle, and a portion having a quick detachable connection with said first portion, said 40 second portion including two members having a threaded connection with each other and having co-operative conductor gripping means, and a binding terminal supported by 45 one of said members.

5. A separable attachment plug comprising an insertible portion having a contact for engagement with the contact of a receptacle, and a portion having a quick detachable connection with said first portion, said 50 second portion including two members having a threaded connection with each other and having co-operative conductor gripping means, and a binding terminal supported by 55 one of said members, the other member being constructed to form a thumb piece.

6. A separable attachment plug comprising an insertible portion having a contact for engagement with the contact of a receptacle, and a portion having a quick detachable connection with said first portion, said 60 second portion including two members having a threaded connection with each other and having co-operative conductor gripping means, and a binding terminal supported by 65

one of said members, the other member being constructed to form a thumb piece, said thumb piece having an opening through which the conductor extends for engagement with the binding terminal.

70

7. A separable attachment plug comprising an insertible portion having a contact for engagement with the contact of a receptacle, and a portion having a quick detachable connection with said first portion, said 75 second portion including two insulating members having co-operative conductor gripping means, a binding terminal supported by one of said members, and means for connecting said members comprising a shell supported by one of said members and having a screw threaded connection with the other.

8. A separable attachment plug comprising an insertible portion having a contact 85 for engagement with the contact of a receptacle, a portion having a quick detachable connection with said first portion, said second portion including two insulating members having co-operative conductor gripping 90 means, a binding terminal supported by one of said members, and means for connecting said members comprising a shell supported by one of said members and having a screw threaded connection with the other, one of 95 said members having an opening through which the conductor extends for engagement with said binding terminal.

9. A quick-detachable separable connector device comprising an insulating support, a 100 quick-detachable contact supported thereby, a second insulating support, a second quick-detachable contact supported thereby for quick-detachable engagement with said first contact, a binding-terminal supported by 105 said second insulating support and electrically connected with said second contact, and conductor-gripping means for the conductor leading to the binding-terminal, also supported by said second insulating support. 110

10. A quick-detachable separable connector device comprising an insulating support, a quick-detachable contact supported thereby, a second insulating support, a second quick-detachable contact supported thereby 115 for quick-detachable engagement with said first contact, a binding-terminal supported by said second insulating support and electrically connected with said second contact, and conductor-gripping means for the conductor leading to said binding-terminal, also supported by said second insulating support, said conductor-gripping means comprising a tubular thumb-piece through which said conductor may extend. 120

11. An electrical device comprising an insulating base having an opening therein, a conductor member supported thereby, and a tubular metal rivet extending through said opening for securing said conductor member 130

to said base, said tubular member being flanged over at each end to secure the parts in place affording a passage for an electrical conductor.

- 5 12. An electrical device comprising an insulating base having an opening therein, a conductor member supported thereby, said base and conductor member having registering apertures, and a tubular metal rivet extending through said apertures and flanged over at each end for securing said conductor member to said base, said tubular member affording a passage for an electrical conductor.
- 10 13. An electrical device comprising an insulating base having an opening therein, a binding-plate supported thereby, said base and binding-plate having registering apertures, and a tubular member extending through said apertures for securing said binding-plate to said base, said tubular member affording a passage for an electrical conductor leading to said binding-plate.
- 15 14. An electrical device comprising an insulating base having an opening therein, a binding-plate supported thereby, said base and binding-plate having registering apertures, a tubular member extending through said apertures for securing said binding-plate to said base, said tubular member aff-
- 20
- 25
- 30

fording a passage for an electrical conductor leading to said binding-plate, and a contact member electrically connected with said binding-plate.

15. An electrical device comprising an insulating base having an opening therein, shell and center contacts supported thereby, a binding-plate also supported thereby and electrically connected with said center contact, and a tubular metal member extending through said opening for securing said binding-plate to said base, said tubular member affording a passage for an electrical conductor leading to said binding-plate.

16. An electrical device comprising an insulating base, a binding-plate supported thereby, said base and binding-plate having registering apertures, shell and center contacts also supported by said insulating base, said center contact being electrically connected with said binding-plate, and a tubular metal member extending through said apertures for securing said binding-plate to said base, said tubular member affording a passage for an electrical conductor leading to said binding-plate.

In witness whereof, I have hereunto subscribed my name.

REUBEN B. BENJAMIN.
